UNITED STATES PATENT OFFICE.

MARJORY A. BOETHING, OF LOS ANGELES, CALIFORNIA.

DESIGN FOR A HANDBAG.

59,577.

Specification for Design.

Patented Nov. 8, 1921.

Application filed September 23, 1920. Serial No. 412,357. Term of patent 7 years.

To all whom it may concern:

Be it known that I, MARJORY A. BOETHING, a citizen of the United States, residing at Los Angeles, in the county of Los Angeles and State of California, have invented a new, original, and ornamental Design for Handbags, of which the following is a specification, reference being had to the accompanying drawing, forming a part thereof.

I claim:

The ornamental design for a handbag, as shown.

MARJORY A. BOETHING.
